UNITED STATES PATENT OFFICE.

FRED R. BELT, OF CHICAGO, ILLINOIS, ASSIGNOR TO FRED R. BELT COMPANY, OF CHICAGO, ILLINOIS, A CORPORATION OF ILLINOIS.

MINER'S ACETYLENE LAMP.

Application filed May 6, 1925. Serial No. 28,287.

Acetylene lamps of this type are usually provided with an upper and lower chamber, the upper chamber being termed the water chamber and the lower being termed the carbide chamber. The carbide chamber is in the form of a cup, which is usually screw threaded to a flange beneath the water chamber so that it may be readily removed for refilling. The refilling is usually not done until the lamp has burned out and then, of course, has to be done in the dark, or in very poor light. The carbide is in a dry lumpy condition and is usually poured into the cup from a tin box or bottle until the cup is about half full. Under the conditions in which the refilling must be done, it usually happens that some of the carbide gets into the screw threads of the cup. Again when the gas is exhausted from the carbide the residue is a lump mass or a wet sludge depending upon the amount of water which has been used in generating the gas, this depending again upon the individual who is using the lamp. When the cup is emptied of this residue, some of it also gets upon the threads of the cup and will be accordingly deposited upon the threads of the flange. This material hardens very quickly and the result is that the cup will become stuck to the flange and can only be removed with great difficulty resulting often in such damage to the threads that a tight joint cannot thereafter be obtained. All lamps in which the cups have been secured by screw threads have been subject to the above objections and the results in all cases have been about the same except that in brass lamps the residue further has a corroding effect upon the metal destroying the threads altogether in time.

It is therefore the object of my invention to provide a simple and efficient means whereby the cup of an acetylene lamp may be readily engaged with or disengaged from the lamp and which will be free from the objections heretofore incident to the use of a threaded engagement between the cup and the lamp.

In the accompanying drawing in which I have shown a selected embodiment of my invention:

Fig. 1 is a side elevation of a lamp having my invention applied thereto, a portion of the structure being broken away and shown in section.

Fig. 2 is a front elevation of the lamp shown in Fig. 1.

Fig. 3 is an enlarged section on the line 3—3 of Fig. 2.

Referring now to the drawings, the upper portion of the lamp which embodies the water chamber is formed as a die casting 1 provided with a depending flange 2 within which is received the flange 3 of the carbide cup 4 which forms the carbide chamber of the lamp. In former constructions these two flanges have been threaded as described above and with the resultant disadvantages.

Extending outwardly from the cup is a shoulder 5 to act as a bearing for the lower edge of the flange 2, a suitable gasket 6 being provided in a groove in the shoulder to engage the edge of the flange. Secured between pairs of ears 7 on the wall of the water chamber are depending locking clamps 8 bent inwardly at their lower ends and adapted to engage outstanding lugs 9 on the shoulder 5. These lugs are preferably wedge shaped, as plainly shown in Fig. 1, and it will be apparent that a simple rotation of the cup in respect to the lamp is all that is necessary to either fasten or unfasten the cup.

The clamps may be made in a variety of forms, but I have found it advantageous to make them in the form shown, in which each clamp is a separate piece including a shank secured between the ears 7 by screws 10. The upper ends of the shanks are bent over at 11 to engage the shoulder 12 on the wall of the water chamber formed by the die casting 1 and thus relieve the screw of any strain due to the weight of the carbide cup. The inwardly bent ends 13 of the shanks are provided with the convex surfaces 14 contacting with the bottoms of the wedge shaped lugs 9. While I have found that these clamps will operate with a fair amount of satisfaction if this convex surface is omitted, nevertheless, by providing such a surface the area of contact between the lug and the clamp is decreased so as to avoid sticking.

From the above it will be apparent that I have provided an acetylene lamp in which the carbide cup forming the bottom of the lamp may be readily applied to and detached from the lamp with a minimum of effort. When attaching the cup to the lamp all that is necessary is to bring together the

flange 2 and shoulder 5, it being noted that the lower edge of the flange 2 contacts throughout with the gasket upon the shoulder. After being brought into this position 5 a simple rotative movement of the cup will bring the lugs 9 into engagement with the clamps 8 and the parts will be securely held together. When it is desired to detach the cup, it is evident that this may be quickly 10 effected without any of the trouble necessary in separating parts which are threaded together. In both attaching and detaching a rotative movement of the shoulder of the cup while held in engagement with the 15 flange is all that is necessary, this rotation being in this instance substantially less than 180°, while to secure the same parts together by threaded engagement would require at least substantially two revolutions 20 of one part in respect to the other, and, as pointed out above, the conditions under which the operation has to be performed are such as to make it desirable to avoid every movement and complication which can 25 possibly be avoided. The clamps effectively secure the parts together and yet because of the convex surface 14 sticking is avoided, the liability of sticking being obviously increased due to the fact that the wet sludge 30 is apt to get in between the clamps and the lugs. Moreover, the clamps are easily and efficiently made and secured to the lamp without any strain being placed upon the fastening means.

I am aware that changes in the form, construction and arrangement of parts may be made without departing from the spirit and without sacrificing the advantages of the in-

vention and I reserve the right to make all such changes as fairly fall within the scope 40 of the following claims.

I claim:

1. A lamp comprising a pair of chambers and means for detachably connecting the chambers including a shoulder upon one of 45 the chambers, spaced ears upon the shoulder, a clamp member having a shank lying between and engaged by the ears, a fastening securing the shank to the shoulder, said shank having at one end a lateral offset portion 50 engaging across the shoulder and also provided at its opposite end with an offset cam portion, and a shoulder on the other chamber with which the cam portion engages.

2. A miner's lamp comprising a water chamber having depending clamps, and a carbide cup having wedged shaped lugs co-operating with said clamps to hold said cup in position, said clamps and lugs being 60 brought into and out of engagement by the rotative movement of said cup in respect to the rest of said lamp, said clamps being provided with convex surfaces engaging with 65 said lugs.

3. A miner's lamp comprising two elements, a water chamber and a carbide cup separable therefrom, one of said elements having a plurality of clamps and the other of said elements having wedge shaped lugs 70 co-operating with said clamps to hold said elements together, said clamps being provided with convex surfaces engaging with said lugs.

FRED R. BELT.
